UNITED STATES PATENT OFFICE.

FRANK W. LANCASTER, OF PHILADELPHIA, PENNSYLVANIA.

AIR-DEFLECTING DEVICE FOR WINDOW-FRAMES.

1,376,210.

Specification of Letters Patent. Patented Apr. 26, 1921.

Application filed April 3, 1920. Serial No. 370,925.

To all whom it may concern:

Be it known that I, FRANK W. LANCASTER, a citizen of the United States, residing at Philadelphia, in the county of Philadelphia 5 and State of Pennsylvania, have invented certain new and useful Improvements in Air-Deflecting Devices for Window-Frames, of which the following is a specification.

One object of my invention is to provide means which can be easily attached to a window frame and which can be moved into various positions to cause air, which would otherwise pass by the window, to be intercepted and deflected into a room so as to 15 supply the room with fresh air and force the foul air therefrom.

Another object is to so construct my invention that it may be easily and quickly moved into a position to serve as a water 20 shed to prevent water from entering the window even though the sash is raised and in this manner the sash can remain open while it is raining without possibility of the rain entering the open window.

25 A further object is to make my invention of a comparatively simple and durable construction.

These objects, and other advantageous ends which will be described hereinafter, I 30 attain in the following manner, reference being had to the accompanying drawings in which—

Figure 1 is a front elevation of a window having my invention thereon so placed as to 35 serve as a deflector as above stated,

Fig. 2 is a view of similar character to Fig. 1 showing my invention in a position acting as a water shed as above stated,

Fig. 3 is a slightly enlarged elevation, 40 partly in section, showing the device of my invention in the position as shown in Fig. 2,

Fig. 4 is a fragmentary perspective view of a portion of the device of my invention in the position shown in Fig. 1,

45 Fig. 5 is a fragmentary section taken on the line 5—5 of Fig. 4,

Fig. 6 is an enlarged end view of a portion of my invention, and

Fig. 7 is a fragmentary elevation of a 50 part of my invention.

Referring to the drawings, 8 represents the frame of a window having vertically 55 slideable sashes 9 and 10 therein. A standard or post 11 has its upper end pivoted in an eyelet 12 which is secured to the lower outer surface of the window sash 9. The lower

end of the post 11 is pivoted in a base 13, which is secured to the lower inner surface of the window frame 8; said base having a number of notches 14 spaced apart radially 60 with respect to the pivotal axis of the post 11. The post 11 immediately above the base 13 has an angular portion 15 upon which slidably fits a sleeve 16 so that while the sleeve 16 is free to slide upwardly when lifted, relative rotation between said sleeve and angular portion is prevented. The sleeve 16 has a finger 17 extending radially therefrom and adapted to enter any of the notches 14. Thus considering that the base 70 13 is fixed the post 11 can be locked against rotation in a number of positions as is clearly obvious from the showing in Fig. 6.

A deflecting vane 19 which is preferably made of sheet metal has a metallic rod 20 75 secured thereto either by soldering, brazing or other suitable manner; said rod having an off-set portion 21 spaced from the surface 22 of the vane; said rod portion having a screw threaded end 23 which has a 80 thumb nut 24 screwed thereon. The rod portion 21 has a lug 25 which extends to the surface 22 of the vane 19 and a lateral lug 26 which extends in a direction toward the surface 22 but stops short thereof to 85 provide a space 27 between its outer end and the surface 22 as shown in Fig. 3.

The post 11 has a brace arm 28 extending upwardly at an incline; said brace arm at its top being formed in an eyelet 29 through 90 which the portion 21 of the rod 20 extends. The eyelet 29 has two recesses 30 and 31 in its front surface which are in horizontal alignment and when in the position shown in Fig. 4 with the vane in an upright position the lug 26 fits into the recess 31 and the portion 21 of the rod 20 extends through a slot 32 formed vertically in the post 11; the nut 24 serving to hold the lug 26 within the recess 31 and thereby secure the vane 19 in its upright position. The post 11 can be swung with the vane 19 thus locked to it in the various positions to intercept air passing by the window and thereby cause the air to be deflected into the window. The 105 post 11 is preferably positioned centrally within the width of the window so that the air will be deflected into the window at one side of the post and foul air will be forced out of the window at the opposite side of 110 the post. The slot 32 extends vertically and is formed by furcations 33 in the post 11.

- Within the height of the slot 32 the furcations 33 are bent angularly as shown at 34 to provide cavities which taper inwardly as clearly shown in Figs. 1, 3 and 4. The rod 5 20 at the inner end of the off-set portion 21 has nubs 35 and 36 projecting therefrom; said nubs extending in directions substantially at right angles to the directions in which the lugs 25 and 26 extend.
- 10 An extension strip 37 has portions 38 which project through slideways 39 on the vane 19. The strip 37 has a notch 40 through which the post 11 projects when the vane is swung into the positions shown in Figs. 2 15 and 3.

When it is desired to swing the vane from the position shown in Figs. 1 and 4 to the positions shown in Figs. 2 and 3, the thumb nut 24 is loosened and the vane is 20 pulled outwardly until the lug 26 moves out of the recess 31. The vane is then turned substantially 90° until the lug 26 can be slid through the eyelet 29 so as to permit the nubs 35 and 36 to position themselves in the 25 recesses 30 and 31 in the eyelet 29. The nut 24 can be backed to permit the vane to be 30 swung on the nubs 35 and 36 as a pivot until the nut 24 is positioned in the cavity 34 as shown in Fig. 3 after which the nut can 35 be tightened and the vane will be held in a position serving as a water shed to prevent water from entering the window as clearly shown in Fig. 3. The strip 37 can be moved upwardly toward the sash so as to embrace 40 the post 11 and in this manner the device is held firm and in close proximity to the window sash so as to permit air to enter through the window to the exclusion of rain.

While I have described my invention as 45 taking a particular form, it will be understood that the various parts of my invention may be changed without departing from the spirit thereof, and hence I do not limit myself to the precise construction set forth, but 50 consider that I am at liberty to make such changes and alterations as fairly come within the scope of the appended claims.

Having thus described my invention, what I claim as new and desire to secure by 55 Letters Patent is:—

1. A device of the character described including a post; a base in which the bottom of the post is pivotally mounted, said base having notches spaced apart; a sleeve rotatably locked to said post but free to slide thereon, said sleeve having a portion adapted to enter any of said notches; and a deflecting vane carried by said post; substantially as described.
- 60 2. A device of the character described including a supporting post; a vane supported by said post and adapted to swing thereon into substantially horizontal and upright positions; and an extension strip movably

connected to said vane and having a notch 65 for embracing said post when the vane is swung into a substantially horizontal position; substantially as described.

3. A device of the character described including a post; a base in which the bottom 70 of the post is pivotally mounted, said base having notches spaced apart, said post having an angular portion; a sleeve fitting said angular portion of the post and adapted to slide thereon in the direction of the height 75 of the post, said sleeve having a finger adapted to enter any of said notches whereby the post can be locked in various pivotal positions; and a deflecting vane carried by said post; substantially as described. 80

4. A device of the character described including a pivotally mounted post having a brace arm thereon providing an eyelet having recesses therein; a deflecting vane; a rod on said vane having a portion spaced from 85 the vane; a lug on said rod adapted to enter one of said recesses; and means for clamping said rod to the post, said lug, when the clamping means is released, being adapted to be swung, with the vane, into a position 90 to slide through said eyelet, said rod having nubs thereon extending in a direction at an angle to said lug and adapted to be moved into said recesses and locked therein by said clamping means after said vane has been 95 turned; substantially as described.

5. A device of the character described including a pivotally mounted post having a brace arm thereon providing an eyelet having recesses therein; a deflecting vane; a rod 100 on said vane having a portion spaced from the vane; a lug on said rod adapted to enter one of said recesses; and means for clamping said rod to the post, said lug, when the clamping means is released, being adapted 105 to be swung, with the vane, into a position to slide through said eyelet, said rod having nubs thereon extending in a direction at an angle to said lug and adapted to be moved into said recesses and locked therein by said 110 clamping means after said vane has been turned, said post having cavities formed therein forming a seat for said clamping means when said vane after being turned is 115 swung into an inclined position; substantially as described.

6. A device of the character described including a pivotally mounted post having a brace arm thereon providing an eyelet having recesses therein; a deflecting vane; a rod 120 on said vane having a portion spaced from the vane; a lug on said rod adapted to enter one of said recesses; means for clamping said rod to the post, said lug, when the clamping means is released, being adapted 125 to be swung, with the vane, into a position to slide through said eyelet, said rod having nubs thereon extending in a direction at an

angle to said lug and adapted to be moved into said recesses and locked therein by said clamping means after said vane has been turned; and an extension strip movably connected to said vane and having a notch for embracing said post; substantially as described.

In testimony whereof I have signed my name to this specification in the presence of two subscribing witnesses.
